UNITED STATES PATENT OFFICE.

ARTHUR C. SEIBAK, OF SAN FRANCISCO, CALIFORNIA.

MOTOR-WHEEL FOR CYCLES.

1,041,519.

Specification of Letters Patent.

Patented Oct. 15, 1912.

Application filed February 3, 1910. Serial No. 541,718.

To all whom it may concern.

Be it known that I, ARTHUR C. SEIBAK, a subject of the King of Denmark, residing at San Francisco, in the county of San Francisco and State of California, have invented certain new and useful Improvements in Motor-Wheels for Cycles, of which the following is a specification.

This invention relates to motor wheels for cycles.

The object of the invention is to provide an article of this character in which the engine shall be rigidly supported from the frame of the machine in such manner as to reduce vibration to a minimum; in which the supply of oil for lubricating and gasoline or other hydrocarbon shall be wholly confined within the hub of the drive-wheel of the machine; and in which the supply of the explosive mixture shall be constant under all conditions of use, thus to insure even and steady running of the machine.

With the above and other objects in view, as will appear as the nature of the invention is better understood, the same consists in the novel construction and combination of parts of a motor wheel for cycles, as will be hereinafter fully described and claimed.

In the accompanying drawings, forming a part of this specification, and in which like characters of reference indicate corresponding parts: Figure 1 is a view in side elevation of a motor wheel constructed in accordance with the present invention, a portion of the structure being removed to expose the interior parts. Fig. 2 is a similar view taken from the opposite side of the wheel to that shown in Fig. 1. Fig. 3 is a transverse sectional view taken through the center of the wheel. Fig. 4 is a detail view showing the connection between the magneto-generator and the spark plug.

Referring to the drawings, F designates a portion of the frame of a motorcycle, and with which the motor wheel is rigidly connected from the supporting axle in the usual manner, and as this frame may be of the common or any preferred construction, further description is deemed unnecessary.

The motor wheel comprises in part a circular main casing or chamber 1 from one side of which projects an arm 2 that is connected with the lower frame-bar f by a clip C, it being understood that there is one of these arms on each side of the chamber. Arranged within the main chamber or cas-

ing 1 is a cylinder casing 4, which is preferably cast integral with the chamber, the latter of which is divided into two compartments 5 and 6, the compartment 5 to contain oil and the compartment 6 gasoline or the like. The casing is provided at its lower end with a circular extension 7 that is provided with two shoulders 8, and to these shoulders is bolted the cylinder 9 which, as usual, is provided with cooling flanges 10 and with a mixing chamber 11 that communicates with the upper portion of the cylinder.

Within the cylinder is arranged a piston 12 of the usual or any preferred construction with which is pivotally connected the upper end of a connecting rod 13, the lower end of which is journaled on the cross-arm 14 of a crank 15 having lateral arms 16 and 17 that are journaled in suitable bearings 18 formed in the lower portion of the cylinder, the arms being each provided in this instance with two packing rings to prevent escape of air from the air-chamber formed by the extension 7. Upon the arm 17 is mounted a pinion 20 that meshes with a gear 21 mounted upon a drive shaft 22, which latter also carries a sprocket wheel 23 that is engaged by a sprocket chain 24 that passes to the sprocket wheel of the treadle shaft, not shown, in the usual manner.

Extending from opposite sides of the cylinder 9, and in axial alignment are bosses 25 and 26, each of which is provided with a reduced threaded extension 27 that extends through the crotches of the frame, and are held rigid therewith by nuts 28. The boss 26 is the longer and has mounted thereon a loose idler pinion 29 a fixed cover plate 30. The gear 21 meshes with the pinions 20 and 29 and is driven by the former and drives the latter, whereby uniformity and steadiness of motion is secured. The motion of the pinion 29 may be employed for driving a magneto if desired.

The casing is provided with two races 31 in which are arranged ball-bearings 32, and these are engaged by the hub 33, which, as clearly shown in Fig. 3, is a two part structure, the opposing edges of which are formed with flanges 34 through which pass bolts or screws 35. The hub sections have connected with them spokes 36 of any preferred construction, and which are combined with a rim 37, as usual. One of the hub sections is provided with an internal gear

38 which is engaged by the gear 21, and by which it is driven. The open side of this gear is closed by the cover plate 30, which protects the same from dust and dirt.

5 As usual, there is arranged adjacent to the mixing chamber a spark-plug 53, which is suitably connected with the magneto-generator.

10 The cylinder is provided with a piston-controlled escape port 54, and with a branch pipe 55 that communicates with the air-chamber and with the external air, and is provided with a ball valve 56 which closes on the compression stroke of the piston and 15 opens on the working stroke.

15 The peculiar advantage of employing a pump, such as shown, for supplying predetermined charges of gasolene to the mixing chamber is that such charges will always be 20 uniform irrespective of the character of the ground over which the machine may be traveling, so that easy and uniform running will be secured.

25 While the improvements herein described are simple in character, they will be found thoroughly effective for the purposes designed, and will coact in the production of an effective and durable form of motor wheel.

30 I claim:

1. A motor wheel, including a main chamber or casing, a cylinder therein, a gasolene reservoir supported by the cylinder, a piston arranged in said cylinder, a piston rod

coupled to said piston, a crank-shaft having 35 connection with said piston rod, a hub revolvably mounted on the main chamber or casing, an internal gear-wheel carried thereby, a pinion carried by said crank-shaft, a drive-shaft journaled on the main chamber or casing, 40 a gear carried thereby and meshing with said pinion, and gear-wheel and a drive sprocket also carried by said drive-shaft.

2. A motor wheel, including a main chamber or casing, 45 a cylinder therein, a gasolene reservoir supported by the cylinder, a piston arranged in said cylinder, a piston rod coupled to said piston, a crank-shaft having connection with said piston rod, a hub revolvably mounted on the main chamber or casing, an internal gear-wheel carried thereby, 50 a pinion carried by said crank-shaft, a drive-shaft journaled on the main chamber or casing, an idler pinion journaled on the cylinder, 55 a drive gear on the drive-shaft meshing with said pinions and internal gear, a drive-sprocket on the drive-shaft, a mixing chamber, means for supplying an explosive mixture thereto, and means for exploding the 60 mixture.

In testimony whereof I affix my signature in presence of two witnesses.

ARTHUR C. SEIBAK.
